UNITED STATES PATENT OFFICE.

GEORGE H. LELAND, OF DAYTON, OHIO, ASSIGNOR OF ONE-HALF TO THE LELAND ELECTRIC COMPANY, OF DAYTON, OHIO, A CORPORATION OF OHIO.

SHORT-CIRCUITING DEVICE FOR MOTORS.

Application filed April 16, 1925. Serial No. 23,524.

This invention relates to short circuiting devices for motors. Electric motors of the type known as repulsion induction motors are started as repulsion motors and after 5 they have attained a predetermined speed are automatically converted into induction motors. This is usually accomplished by providing a short circuiting element for the commutator bars comprising a series of contact members or weights adapted to be moved by centrifugal force into short circuiting contact with the commutator bars, a 10 yieldable member acting on the contact weights to resist their outward movement and to retract the same into inoperative 15 positions when the speed of the motor is reduced below a predetermined point.

One object of the present invention is to provide a short circuiting device of this 20 character which will be simple in construction, highly efficient in operation and which can be produced at a relatively low cost.

A further object of the invention is to provide a short circuiting device of this character in which the contact weights will be 25 retained in their proper relative positions and will be caused to move in unison.

A further object of the invention is to provide a short circuiting device of this 30 character in which the contact weights will have butt contact with the commutator bars but in which the contact will be broken in such a manner as to prevent injury to the contact surfaces by burning.

Other objects of the invention will appear 35 as the device is described in detail.

In the accompanying drawings Fig. 1 is 40 an end elevation, partly broken away, of a short circuiting device embodying my invention; Fig. 2 is a longitudinal sectional view taken centrally of a short circuiting device embodying my invention and of the commutator; Figs. 3 to 7 inclusive are detail views showing the relation of the contact portions of the weights to the commutator bars; Fig. 8 is an edge view of one of the dividing weights; Fig. 9 is a face view of the same; Fig. 10 is a face view of one of the loose weights; Fig. 11 is an edge view of 45 one of the loose weights; and Fig. 12 is a detail view of the connecting ring.

In these drawings I have illustrated one embodiment of my invention and have shown the same in connection with a commutator comprising a body portion 1 rigidly 50

mounted on an armature shaft 2 and having the usual circumferential series of contact bars 3 which are insulated one from the other and from the body 1 of the commutator. I have not shown the motor as a 60 whole nor the wiring for the commutator as these are not necessary to an understanding of the invention. Arranged circumferentially of the shaft 2 is a short circuiting element comprising an annular series of contact 65 members or weights which are adapted to be moved by centrifugal force into short circuiting contact with the commutator bars 3. In the present construction these contact weights are of two kinds, the weights 4 70 being loosely mounted and the weights 5 being connected one with the other, as will be hereinafter explained. This series of contact weights are confined between the forward face of the commutator, that is, the 75 face remote from the motor, and a plate or disk 6, which is mounted on the shaft 2, and which may, if desired, have both rotatory and axial movement with relation thereto, but the axial movement of which, away 80 from the commutator, is limited by a stop, such as a split ring 7 mounted in a groove 8 in the shaft 2. Cooperating with the contact weights is a yieldable member which serves to resist the outward movement of the 85 weights and to retract the same into inoperative positions when the centrifugal force which has moved them outward is discontinued. In the present arrangement this yieldable member also serves to press the contact portions of the weights firmly in engagement with the face of the commutator and to hold the weights against lateral displacement, that is, displacement lengthwise of the shaft 2. To this end each of the 90 weights has its outer end shaped to provide a shallow recess as shown at 8 the bottom or lowest radial part of which is purposely located in closer proximity to the plate 6 than to the commutator 1. The yieldable member, preferably a helical coil spring 17 tending to seek the bottom or lowest radial part of this recess, engages the plate 6 holding it 95 yieldingly against the lock ring 7 and its reaction upon the contact members holds them in similar frictional contact with the face of the commutator. Consequently the yieldable band not only serves to resist the outward movement of the weights and to retract the same but it also serves the addi- 100 105 110

tional purpose of maintaining a constant frictional contact between the weights and the commutator, between the band and the disk, and between the disk and the lock ring. These various frictional engagements can be regulated in production by varying the shape of the outer ends of the weights and they always serve to insure smooth operation as nothing is left loose to rattle or chatter, while uniform wear of the parts is attained by the fact that the device rotates slightly with respect to the commutator as the motor starts and stops. Due to the fact that the yieldable band is of an elastic character there is very little relative movement of the band with relation to the weights and the frictional contact between the weights and the band is reduced to a minimum.

The several weights 4 and 5 are provided on their rear edges, that is, the edges adjacent to the face of the commutator, with projections 9 and 10 which bear against the face of the commutator and form the sole points of contact between the weights and the commutator, thus serving to minimize the friction between these parts. The projection at the outer end of each weight constitutes the contact portion of the weight, which engages the commutator bar, and this contact portion or projection 9 and the commutator bars are so shaped and arranged with relation one to the other that the weights will engage the bars with a butting contact but there will be no sparking between the main contact surfaces when the weights move away from the bars, which would tend to burn the surfaces and prevent the proper contact. In that form of the device here shown the commutator bars 3 extend forwardly beyond and overhang the face of the body of the commutator and also overhang the adjacent portions of the weights. The inner corners of the overhanging portions of the bars are cut away to provide arcuate recesses 11 which constitute the contact portions of the bars and which are here shown as arcs of substantially ninety degrees. The contact portion or projection 9 of each weight has its outer edge curved to conform to the curvature of the recess or seat in the commutator bars. Preferably the contact edge of the weight is described about an axis so arranged that when this edge is in engagement with the commutator bar the center will be substantially in longitudinal alignment with the inner edge of the commutator bar and in substantially radial alignment with the forward end of that bar. Inasmuch as the curved recess in the commutator bars conforms to the curvature of the edge of the weight it will be obvious that this arc is described about this same center. When the contact weight is in its outer position it will be in full contact with one or more of the commutator bars through

an arc of ninety degrees, which arc lies between the horizontal and vertical radii of the circle of which it forms a part. Consequently when the weight moves radially, that is, along the line of the vertical radius of said circle, all portions of the contact surface of the weight will simultaneously move out of engagement with the commutator bar but the outer portion of the contact surface of the weight will move away from the adjacent portion of the bar more rapidly than will the inner portion of that contact surface, as will be apparent from an examination of Figs. 3 to 7. Any tendency of the current to bridge the gap between the two contact surfaces, as they separate, will naturally take place at the point where the distance between the members is the shortest, that is, at the lower portions of the contact surfaces, and any burning which may result from this will be confined to these portions of the contact surfaces and the major portions of those surfaces will not be burned but will always be in a condition to effect a perfect electrical contact.

When the short circuiting element consists of loose weights, such as are shown at 4, there is sometimes a tendency for these weights to move outwardly at different times, due to variations in frictional resistance, or to other causes, and, further, the spacing between the weights when they are in their outermost positions is sufficient to permit one or more of the weights to get out of its proper position with relation to the other weights and thereby cause the weights to pile up or to interlock in such a manner as to prevent proper retraction thereof. In the construction here shown the loose weights 4 are divided into substantially equal groups by the dividing weights 5 which, as has been above explained, are connected one to the other so as to cause them to move in unison. In that form illustrated each of the dividing weights comprises a relatively flat radially extending portion of a width substantially equal to the width of the loose weights. The inner portion of this weight is bent laterally and extends about the circumference of the shaft 2 for a distance of approximately ninety degrees, as shown at 12, the loose weights having their forward edges cut away at the inner ends thereof to form a recess 13 in which these laterally extending portions of the dividing weights are arranged. Any suitable number of dividing weights may be employed but, as here shown, there are six of these dividing weights and consequently the laterally extending portions thereof overlap and the overlapping portions are so shaped as to prevent them coming in contact one with the other. Loosely mounted on the shaft 2 is a connecting member with which the ends of the laterally extending portions

- of the dividing weights are pivotally connected. In the present construction this connecting member comprises a flat ring 14 which is mounted on the shaft 2 for rotatory movement with relation thereto and it is provided in its inner periphery with a series of notches 15 adapted to receive lugs 16 extending laterally from the inner ends of the inner portions 12 of the dividing weights.
10. The arrangement of the lugs within the notches is such that the inner ends of the weights will have no appreciable radial or circumferential movement with relation to the ring but will have free pivotal movement in the notches. When one of the dividing weights 5 tends to move outwardly, due to centrifugal force, its outer portion will move in a substantially radial direction and in order to permit of this movement the inner end of that weight must be laterally displaced with relation to the shaft. The inner ends of the several dividing weights being connected one with the other it will be obvious that the lateral displacement of the inner end of one weight will cause the like displacement of the inner ends of all dividing weights and these weights will be caused to move in unison. Further, inasmuch as one of the dividing weights 30 cannot move independently of the others it necessarily follows that none of the weights will move outwardly until the centrifugal force is sufficient to move all of them outwardly. The dividing weights separate the loose weights into relatively small groups and the space between the loose weights of each group when they are in their outermost positions, is not sufficient to permit of the displacement of one weight with relation to the other.
- While I have shown and described one embodiment of my invention I wish it to be understood that I do not desire to be limited to the details thereof as various modifications may occur to a person skilled in the art.
- Having now fully described my invention, what I claim as new and desire to secure by Letters Patent, is:
50. 1. In a device of the character described, the combination with a shaft, and a commutator mounted on said shaft and comprising a series of bars, of an annular series of substantially radial contact members arranged circumferentially of said shaft and movable in substantially straight lines by centrifugal force into short circuiting contact with said commutator bars, means for connecting the inner ends of a part of said contact members one to the other to cause them to move in unison, and a yieldable device acting on said contact members to resist their outward movement.
55. 2. In a device of the character described, the combination with a shaft, and a com-
- mutator mounted on said shaft and comprising a series of bars, of an annular series of substantially radial contact members arranged circumferentially of said shaft and movable in substantially straight lines by centrifugal force into short circuiting contact with said commutator bars, a part of said contact members having portions extending inwardly and laterally with relation to the other contact members, means for connecting the inner ends of the first mentioned contact members one to the other to cause said contact members to act in unison, and a yieldable device acting on all of said contact members to resist their outward movement.
60. 3. In a device of the character described, the combination with a shaft, and a commutator mounted on said shaft and comprising a series of bars, of an annular series of contact members arranged circumferentially of said shaft and movable by centrifugal force into short circuiting contact with said commutator bars, a member mounted on said shaft for rotatory movement, and means for so connecting a part of said contact members with said rotatable member that said part of said contact members will be caused to move outwardly in unison, said part of said contact members being arranged to divide the other contact members into groups, and a yieldable device acting on all of said contact members to resist their outward movement.
65. 4. In a device of the character described, the combination with a shaft, and a commutator mounted on said shaft and comprising a series of bars, of an annular series of contact members arranged circumferentially of said shaft and movable by centrifugal force into short circuiting contact with said commutator bars, a part of said contact members having portions extending inwardly beyond the adjacent portions of the other contact members and about said shaft, and a member mounted on said shaft for rotatory movement with relation thereto and connected with said inner portions of said contact members to cause the latter to move in unison, and a yieldable device acting on all of said contact members to resist their outward movement.
70. 5. In a device of the character described, the combination with a shaft, and a commutator mounted on said shaft and comprising a series of bars, of an annular series of contact members arranged circumferentially of said shaft and movable by centrifugal force into short circuiting contact with said commutator bars, a member mounted on said shaft for rotatory movement with relation thereto, a part of said contact members having inner portions extending circumferentially of said shaft and pivotally connected to said rotatable mem-

ber, the last mentioned contact members being arranged to divide the other contact members into groups, and a yieldable device acting on said contact members to resist their outward movement.

6. In a device of the character described, the combination with a shaft, and a commutator mounted on said shaft and comprising a series of bars, of an annular series of 10 contact members arranged circumferentially of said shaft and movable by centrifugal force into short circuiting contact with said commutator bars, a ring loosely mounted on said shaft and having recesses therein, a 15 part of said contact members having inner portions extending circumferentially of said shaft and provided at their ends with parts extending into the respective recesses in said ring to pivotally connect said weights 20 with said ring, and a yieldable member acting on all of said contact members to resist their outward movement.

7. In a device of the character described, the combination with a shaft, and a commutator mounted on said shaft and comprising a series of bars, of an annular series of 25 contact members arranged circumferentially of said shaft and movable by centrifugal force into short circuiting contact with said 30 commutator bars, the several contact members having portions of their inner ends cut away to provide an annular recess extending about said shaft, a part of said contact members having inner portions arranged in said 35 annular recess and extending circumferentially of said shaft, a connecting member mounted on said shaft for rotatory movement with relation thereto, said inner portions of said part of said contact members 40 being pivotally connected with said connecting member, and a yieldable device acting on the several weights to resist their outward movement.

8. In a device of the character described, 45 the combination with a shaft, and a commutator mounted on said shaft and comprising a series of bars, of a plurality of groups of contact members arranged circumferentially of said shaft for movement by centrifugal force into short circuiting contact 50 with said commutator bars, other members having parts arranged between the respective groups of said contact members and movable outwardly by centrifugal force and 55 also having laterally extending inner portions arranged circumferentially of said shaft, a device supported on said shaft for rotatory movement relatively thereto and having pivotal connection with the inner 60 portions of the last mentioned members to cause them to move outwardly in unison, and a yieldable device acting on all of said members to resist their outward movement.

9. In a device of the character described, 65 the combination with a shaft, and a com-

mutator mounted on said shaft and comprising a series of bars, of a disk mounted on said shaft and spaced from the face of said commutator, an annular series of contact members mounted in the space between said 70 disk and said commutator for radial movement by centrifugal force into short circuiting contact with said commutator bars, each of said contact members having a curved recess in its outer end, said recess sloping 75 from said commutator toward said disk, and a contractile band encircling said contact members and engaging the recessed ends thereof and said disk to resist the outward movement of said contact members and to 80 press the same against said commutator.

10. In a device of the character described, a shaft, a commutator mounted on said shaft and comprising bars, the ends of which overhang the face of said commutator, the 85 overhanging portions of said bars having their inner corners cut away to form arcuate recesses, a series of weights arranged circumferentially of said shaft for movement in substantially straight lines by centrifugal 90 force into short circuiting contact with said commutator bars, said weights having contact portions in sliding contact with the face of said commutator and curved to conform to the contour of the arcuate recesses in said 95 commutator bars, and a yieldable device acting on said weights to resist their outward movement and to press said contact portions thereof against said commutator.

11. In a device of the character described, 100 a shaft, a commutator mounted on said shaft and comprising bars, the ends of which overhang the face of said commutator, a series of weights arranged circumferentially of said shaft and in sliding contact with the 105 face of said commutator and movable by centrifugal force into short circuiting contact with said commutator bars, each of said weights having a contact portion the edge of which conforms to the arc of a circle described about a center spaced substantially equal distances from the outer end of said weight and from that edge of said weight which is adjacent to said commutator, the overhanging ends of said commutator bars 110 having their inner corners cut away to form arcuate recesses which conform to the shape of the contact portions of said weights, and a yieldable device acting on said weights to 115 resist their outward movement and to press said contact portions thereof against the face of said commutator.

12. In a device of the character described, 120 a shaft, a commutator mounted on said shaft and comprising commutator bars, said bars being so constructed as to present a curved contact surface, a series of weights arranged circumferentially of said shaft and arranged to be moved in substantially straight lines 125 under centrifugal influence into short cir- 130

- cuiting contact with said bars, each of said weights being provided with a curved contact surface the curvature of which conforms to the curved contact surface of the 5 bars, the weights and the commutator bars being respectively so proportioned with respect to their opposed contact surfaces that as the weights move outwardly they effect substantially full faced engagement as short 10 circuiting contact occurs.
13. In a device of the character described, a shaft, a commutator mounted on said shaft and comprising commutator bars, said bars being so constructed as to present a curved 15 contact surface, a series of weights arranged circumferentially of said shaft and arranged to be moved under centrifugal influence into short circuiting contact with said bars, each of said weights being provided with a curved 20 contact surface the curvature of which conforms to the curved contact surface of the bars, the weights and the commutator bars being respectively so proportioned that as the weights move outwardly toward the 25 commutator bars the opposed curved surfaces of the weights and the bars will be in

progressively varying diverging relation until the instant of contact.

14. In a device of the character described, a shaft, a commutator mounted on said shaft 30 and comprising commutator bars, said bars being so constructed as to present a curved contact surface, a series of weights arranged circumferentially of said shaft and arranged to be moved under centrifugal influence into 35 short circuiting contact with said bars, each of said weights being provided with a curved contact surface the curvature of which conforms to the curved contact surface of the bars, the weights and the commutator bars being respectively so proportioned that as the weights move outwardly toward the commutator bars the opposed curved surfaces of the weights and the bars 40 will be in progressively varying diverging relation until the instant of contact, but will effect substantially full face engagement as short circuiting contact occurs. 45

In testimony whereof, I affix my signature hereto.

GEORGE H. LELAND.
